UNITED STATES PATENT OFFICE.

CLAUDE E. REESE, OF CANEY, KANSAS.

GAS-PURIFIER.

1,240,368.

Specification of Letters Patent. Patented Sept. 18, 1917.

Application filed January 10, 1916. Serial No. 71,284.

To all whom it may concern:

Be it known that I, CLAUDE E. REESE, a citizen of the United States, residing at Caney, county of Montgomery, and State of 5 Kansas, have invented certain new and useful Improvements in Gas-Purifiers, of which the following is a specification.

My invention relates to gas purifiers and particularly to apparatus for removing mechanically the suspended impurities in gases. More particularly my invention relates to an apparatus for removing particles of tar and dust from manufactured gas or the particles 10 of oil and dust from natural gas.

The object of my invention is to provide 15 an improved apparatus for rapidly and efficiently removing the suspended impurities from gas. A further object of my invention is to provide improved means for maintaining the interior walls of the apparatus in proper condition to receive and retain the particles of dust so that they may be carried off with the tar and oil. A further object 20 of my invention is to provide, in an apparatus of the class described, means whereby the heavy tar may be removed from the apparatus and that without permitting the escape of gas or materially interfering with the operation of the device. A further object 25 of my invention is to provide an apparatus as mentioned equipped with means to maintain a practically constant velocity of the gas through the apparatus irrespective of the increase or diminution of the volume 30 of gas supplied to the apparatus. A further object of my invention is to provide a device of the class mentioned which shall be of small size and of low cost to install and maintain. Other objects will appear here- 35 inafter.

With these objects in view my invention consists generally in a casing provided with a vertically disposed spiral wall forming a spiral passage way for the gases and equipping said walls with baffles to receive and retain the impurities. My invention further consists in a device as mentioned further characterized by providing the baffles with apertures to form jets of the gas as it passes 45 through the apparatus and in arranging these apertures in staggered relation on the several baffles so that the gas jets from the apertures in one baffle will impinge against the unbroken portion of the walls of the 50 next baffle. My invention further consists in a device as mentioned in which the casing 55

is provided with an inlet and an exhaust chamber in communication with the spiral passage way, the inlet chamber decreasing in cross sectional area as it approaches the entrance to the passage way and the exhaust chamber increasing in cross sectional area as it recedes from the exhaust end of the passage way. My invention further consists in providing an apparatus as mentioned further characterized by a steam jet arranged to enter the inlet chamber in alignment with the entrance to the spiral passage way and to traverse the inlet opening to said chamber whereby moisture may be supplied to the 60 gas and distributed therewith to moisten the particles of dust, etc., and to maintain the spiral walls and the baffles thereon in moist condition so as to receive and retain the impurities; also to maintain the tar particles 65 in a semi-fluid condition so that they will flow downwardly on the baffles and the spiral walls and also serve as a medium to entrap the particles of dust and other impurities. My invention further consists in a 70 device as mentioned in which the casing is provided adjacent the bottom with a perforated plate upon which the spiral walls are adapted to rest and forming below the same a tar chamber to receive the tar and com- 75 mingled impurities separated from the gas. My invention further consists in a gas separator as mentioned provided with a discharge outlet or over flow arranged above the lower ends of the spirals thereby forming 80 a seal for the gases. My invention further consists in providing an auxiliary or clean out chamber adjacent the bottom of the separator and in open communication with the tar chamber, said clean out chamber 85 extending considerably above the communicating opening and provided with clean out openings equipped with suitable closures. My invention further consists in a separator equipped with the clean out 90 chamber as mentioned further characterized by having the clean out chamber provided with an over flow or liquor outlet adjacent the upper portion thereof and a sight opening in said over flow to ascertain the character 95 of the fluid passing through the over flow. My invention further consists in a separator and clean out chamber as mentioned further characterized by a pressure equalizer to maintain the level of the liquor 100 within the clean out chamber at the same height as the level of the liquor in the sepa- 105

rator. My invention further consists in a centrifugal separator in which the discharge is provided with means for regulating the depth of the fluid within the separator so as 5 to maintain a substantially constant velocity of the gas irrespective of the volume supplied to the separator. My invention further consists in a separator and discharge as mentioned in combination with means 10 governed by the pressure of gas within the separator for automatically regulating the position of the discharge so as to vary the cross sectional area of the spiral passage way proportionately to the volume of gas supplied. My invention further consists in a gas separator and regulator as mentioned 15 in which the regulator is arranged to shift the discharge outlet slowly so as to be responsive to substantial changes in the volume of gas supplied but will be practically 20 irresponsible to the slight or rapidly fluctuating changes in the volume. My invention further consists in various details of construction and arrangement of parts all 25 as will be fully described hereinafter and particularly pointed out in the claims.

My invention will be more readily understood by reference to the accompanying drawings forming a part of this specification and in which—

Figure 1 is an elevation of a gas separator embodying my invention in its preferred form, portions being broken away to more clearly illustrate the device,

Fig. 1^a is a detail front elevation of the lower portion of the separator, showing the lower part of the clean out chamber in section,

Fig. 2 is a horizontal section on the line x—x of Fig. 7, upon an enlarged scale.

Fig. 3 is a similar view taken through the tar chamber on substantially the line y—y of Fig. 7, and looking upwardly in the direction of the arrows,

Fig. 4 is a detail view illustrating the arrangement of the baffles on the spiral walls and the gas tight joint between the upper edges of the spiral and the top of the casing,

Fig. 5 is a section on the line z—z of Fig. 4,

Fig. 6 is a view similar to Fig. 5 illustrating a modified form of baffle,

Fig. 7 is a view similar to Fig. 1 showing a separator embodying my invention without the clean out chamber and equipped with means for automatically regulating the depth of the liquor within the separator,

Fig. 8 is a detail view illustrating a modified form of regulator, and

Fig. 9 is a detail plan view of the same.

Referring now to the drawings 1 indicates the casing provided at the upper end with a top closure 2 and at the lower end with 65 a bottom closure 3. Adjacent the lower end

the casing is provided with a horizontal plate or partition 4 dividing the casing into a large upper separating chamber 5 and a lower or tar chamber 6.

In horizontal cross section the casing may be varied in shape as found necessary in designing the device for the particular purpose to which it is to be put but I prefer the form shown in the drawings. As shown therein the casing comprises two vertically disposed shell portions, one being substantially semi-cylindrical, as at 1' terminating in flared edges 1'' and the other being preferably a flat plate 1^a provided at its sides with turned flanges 1^b which are secured at their extreme edges to the edges of the portions 1'', as by rivets 1^c. See Figs. 2 and 3. This design is found to be practical for purifying manufactured gas but in purifying natural gas, particularly when under high pressure, it may be found more practical to make the casing entirely cylindrical; but as this amounts to merely a matter of design I have not illustrated this construction in the drawings.

Arranged within the separating chamber 5 is a pair of spiral members 7 and 8 which are symmetrically coiled within each other forming a uniform gas passageway 9 between them. The outer end of the member 7 is secured, as by rivets, to the center of the front plate 1^a as shown clearly in Fig. 2 and the corresponding end of the member 8 is secured to the member 1' as at 10, at substantially ninety degrees from the attachment of the member 7 to the casing wall. With this construction two chambers 11 and 12 are formed at each side of the front of greater cross sectional area than that of the passage way 9. The chamber 11 constitutes an inlet chamber and the chamber 12 an outlet chamber and it will be noted that the passage way 9 extends from the chamber 11 to the chamber 12 by first passing between the members 7 and 8 in a spiral course to the center and then reversing its direction returns between said members to the chamber 12. An inlet pipe 13 communicates with the chamber 11 and an exhaust pipe 14 communicates with the outlet or exhaust chamber 12. It will be noted also that as the gas passes from the chamber 11 to the passage way 9 it is gradually restricted and that as it emerges from the passage way it gradually expands into the chamber 12. By this arrangement the gas will enter the casing at a certain velocity and the velocity will increase as it approaches the passage way. In passing through the passage way the curvature increases to the center and then gradually decreases and finally expands into the chamber 12 to pass out at the exhaust 14 at substantially the same velocity as it entered at 13. In thus passing through the spiral

115

105

110

115

120

125

130

passage way the gas is subjected to an intense centrifugal action which tends to throw all of the particles or impurities against the outermost wall of the passage way.

To increase the efficiency of the device, so that a small separator may effectually purify the gas I provide the inner faces of the spirals 7 and 8 with a plurality of spaced vertically disposed baffles 15. These are preferably substantially semi-circular in cross section as shown in Figs. 2 and 5 with their concavities presented to the current of gas and are provided with base flanges 16 by means of which they are secured to the spiral walls. The inner or free edges of the baffles are beveled or inclined as at 17 (see Fig. 5) to lessen the friction of the gas passing through the device and also to assist the baffles in pocketing or entrapping portions of the gas as it rushes past the same. The baffles 15 are preferably provided with a plurality of apertures 18 and these apertures are arranged, in the successive baffles in staggered relation as shown in Fig. 4, so that the gas which will pass in jets through the apertures 18 will impinge against the wall of the next succeeding baffle between the apertures, thereby facilitating the depositing of the tar and other impurities on the baffles. In assembling the device the baffles are secured to the plates 7 and 8 before the latter are coiled into their spiral form.

If preferred the baffles may be formed of angle irons 19 as shown in Fig. 6. In such case these baffles will also be provided with apertures 18 arranged in staggered relation as above described. 7^a indicates braces connecting the several convolutions of the spiral walls to prevent vibration of the same when the device is in operation.

The impurities may be more readily removed from the gas when they are moistened, and to this end I provide a steam inlet pipe 20 arranged to inject steam into the chamber 11 in alignment with and in the direction of the entrance to the passage way 9 and also so as to traverse the mouth of the inlet pipe 13. This construction insures a thorough mixing of the steam with the gas, thereby efficiently moistening the latter and also assist the gas in entering the passage way 9. The steam also keeps the particles of tar in a semi-fluid condition so as to flow slowly down the surfaces of the walls 7 and 8 and the baffles 15. The steam is preferably exhaust steam or steam at a low temperature to avoid vaporizing the oils in the tar or the free oils that have been separated from the gas.

The spiral baffle plates 7 and 8 extend from the top closure 2 to the diaphragm or horizontal partition 4. At the upper end the passage ways are sealed by a rubber plate

or gasket 21 arranged between the upper edges of the walls 7 and 8 and the top 2, as shown in Fig. 4; and the lower end of the passage way is closed by a water seal herein-after described.

Extending from the bottom of the tar chamber 6 is a discharge outlet 22 terminating in a discharge spout or over flow outlet 23 arranged an appreciable distance above the bottom 4. A water supply pipe 24 communicates as at 25 with the tar chamber and maintains a water level *a* in the separating chamber at the height of the discharge spout, as indicated in Fig. 1. The plate 4 is provided with a plurality of apertures 26 preferably in spiral arrangement to conform to the spiral passage way 9. The tar and impurities collected on the surfaces of the spiral walls and the baffles will flow downwardly through these apertures 26 into the tar chamber and the tar, oil and water will pass off through the discharge outlet 22 and spout 23 to the tar separator line 27.

28 indicates the clean out chamber which is arranged at the front of the separator shell 1. This extends upwardly above the liquor level within the casing and is in open communication with the tar chamber 6 through an opening 29 formed in the front wall 1^a below the plate 4. The chamber 28 is provided with a liquor over flow pipe 30 communicating with a small shell or casing 31 into which the upper end of a vertically disposed discharge pipe 32 extends. The upper end of the pipe 32 is maintained at the height of the desired liquor level *a* and to this end the pipe 32 may be vertically adjusted within the casing. The front of the casing is provided with a sight opening closed by a glass plate 33. When the accumulation of heavy tar is such that the level *b* thereof reaches the over flow 30, this fact may be ascertained by the operator by sighting through the sight plate 33, the appearance of the tar being an indication that the accumulation of tar within the apparatus should be removed.

To facilitate removing the tar the top of the clean out chamber 28 is provided with a pair of clean out openings 34 equipped with closures 35 so arranged and hinged as at 36 to permit the same to be swung out of the way of the operator when cleaning the device.

In order that the level of the fluids within the clean out chamber shall be the same as the levels within the separator shell it is necessary to provide means for equalizing the pressure and to this end a pipe 37 is extended from the casing 1 and provided with branches 38 and 39 which communicate with the upper portions of the chamber 28 and shell 31 respectively. 40 indicates a valve in the pipe 37 intermediate the shell 1 and the branch pipe 38. When it is desired

to clean out the chamber 28 the valve 40 is closed after which the closures 35 may be opened and the tar removed without interfering with the operation of the separator or permitting the escape of gas, sufficient tar, oil or liquor being retained in the bottom of the device to form a seal for the aperture 29.

As the gas is purified by centrifugal force it is obvious that it must pass at a considerable velocity through the passage way 9. If the gas were delivered at a substantially uniform volume and pressure to the device this necessary velocity would be maintained at all times; but in practice the volume of gas and its pressure, as delivered to the separator, will under some conditions, vary considerably and for this reason I provide means for automatically maintaining the desired velocity of the gas in the separator. This is accomplished by varying the cross sectional area of the passage way 9 inversely proportionately to the volume of gas delivered to the chamber 11. To this end I provide means, controlled by the pressure of gas within the chamber 11 for automatically raising and lowering the discharge spout 23 so as to raise or lower the water level *a*. Although this may be accomplished by various means I find the device shown in Fig. 7 and hereinafter described, efficient for the purpose.

Arranged adjacent the casing 1 is a fluid receptacle 41 in which rests a gas bell 42. A pipe 43 extends from the chamber 5 into open communication with the bell 42. See Fig. 7. A balance beam 44 is mounted upon a shaft 45 and has one end connected by a flexible member 46 with the bell 42 and suspended from the opposite end by a flexible member 47 is a weight 48 which balances the weight of the bell 42. Fixed to the shaft 45 is a sprocket wheel 49 connected by a sprocket chain to a shaft 50 and upon the shaft 50 is a pinion 51 meshing with a rack 52 fixed to and extending vertically upwardly from the discharge spout 23. It is obvious that upon increase of pressure in the chamber 5 the bell 42 will be caused to rise thereby lowering the spout 23 and increasing the cross sectional area of the passage way 9 by lowering the water level *a*. Upon decrease of pressure in the chamber 5 the bell 42 will drop thereby raising the spout 23, hence the water level *a*, and thereby decreasing the cross sectional area of the passage way and maintaining the necessary velocity of the gas as it passes through the separator.

To avoid the regulator acting too quickly, or with minor fluctuations of pressure I equip the bell 42 with a bottom 43 and provide the same with an aperture 54 through which the pipe 43 extends, said aperture being but slightly greater in diameter than

said pipe so as to limit the speed with which the fluid may be received into or discharged from the bell.

If desired, the device may be equipped with means whereby the water level, hence the cross sectional area of the gas passage, may be varied manually to certain fixed limits, thereby dispensing with the automatic regulator above described. To this end the discharge 22 terminates in a stand pipe 55 the upper end of which is at substantially the highest level ever desired for the water in the separator. From the stand pipe 55 extend discharge spouts 56, 57, 58 and 59 arranged at different levels and each equipped with a valve 60 and all discharging into the tar separator line 27, see Figs. 7 and 8. It is obvious that by manipulating the valves 60 the water level *a* may be maintained at any of the four levels desired.

While I have described the preferred form of embodiment of my invention it is obvious that the device may be varied within the limits of the appended claims, to adapt the same for various uses and under various conditions under which it may be used, without departing from the spirit of my invention.

I claim:

1. In a device of the class described, a casing, a pair of intercoiled spiral walls in said casing forming a passage way between them, said casing being provided with inlet and outlet ports in communication with the ends of said passage ways, a plurality of spaced vertically disposed baffles arranged on the outer walls of said passage way, each of said baffles being provided with a series of perforations and the perforations in adjacent baffles being arranged in staggered relation, substantially as described.

2. In a device of the class described, a casing, a pair of intercoiled spiral walls in said casing forming a passage way between them, said casing being provided with inlet and outlet ports in communication with the ends of said passage ways, a plurality of spaced vertically disposed baffles arranged on the outer walls of said passage way, said baffles comprising flanges curved in horizontal section to form pockets, substantially as described.

3. In a device of the class described, a casing, a pair of intercoiled spiral walls in said casing forming a passage way between them, said casing being provided with inlet and outlet ports in communication with the ends of said passage ways, a plurality of spaced vertically disposed baffles arranged on the outer walls of said passage way, said baffles comprising flanges curved to form pockets and each provided with a series of perforations and the perforations in adjacent baffles being in staggered relation, substantially as described.

4. In a device of the class described, a cas-

ing, a pair of intercoiled spiral walls in said casing forming a passage way between them, said casing being provided with inlet and outlet ports in communication with the ends of said passage ways, a plurality of spaced vertically disposed baffles arranged on the outer walls of said passage way, said baffles comprising flanges curved to form pockets and the inner or free edges of said flanges being inwardly beveled, substantially as described.

5. In a device of the class described, a casing, a pair of intercoiled spiral walls in said casing forming a passage way between them, said casing being provided with inlet and outlet ports in communication with the ends of said passage ways, a plurality of spaced vertically disposed baffles arranged on the outer walls of said passage way, said 15 baffles comprising flanges curved to form pockets and the inner or free edges of said flanges being inwardly beveled, and said flanges each being provided with a series of perforations and the perforations in adjacent baffles being arranged in staggered 20 relation, substantially as described.

6. In a device of the class described, a casing, a pair of intercoiled spiral walls arranged within said casing forming a passage way between them, said casing being provided with inlet and outlet ports, the walls of said casing and said spiral walls being arranged to form inlet and outlet 30 chambers in communication with said ports and the respective ends of said passage way with the inlet chamber tapered toward the inlet end of the passage way and the outlet chamber flared from its end of the passage way, substantially as described.

40 7. In a device of the class described, a casing, a spiral wall in said casing forming a passage way, a water seal for the lower end of said passage way, said casing being provided with the clean out opening below 45 the level of said water seal, a clean out chamber in communication with said casing through said clean out opening, there being an aperture in the upper portion of said chamber, and a closure for said aperture, 50 substantially as described.

8. In a device of the class described, a casing, a spiral wall in said casing forming a passage way, a water seal for the lower end of said passage way, said casing being 55 provided with a clean out opening below the level of said water seal, a clean out chamber in communication with said casing through said clean out opening, there being an aperture in the upper portion of said 60 chamber, a closure for said aperture, and means for equalizing the pressure within said casing and said chamber, substantially as described.

9. In a device of the class described, a 65 casing, a spiral wall in said casing forming

a passage way, a water seal for the lower end of said passage way, said casing being provided with a clean out opening below the level of said water seal, a clean out chamber in communication with said casing 70 through said clean out opening, there being an aperture in the upper portion of said chamber, a closure for said aperture, a pipe extending from said casing above said water seal and communicating with the upper portion of said chamber and a valve in said pipe, substantially as described.

10. In a device of the class described, a casing, a spiral wall in said casing forming a passage way, a water seal for the lower 80 end of said passage way, said casing being provided with a clean out opening below the level of said water seal, a clean out chamber in communication with said casing through said clean out opening, there being 85 an aperture in the upper portion of said chamber, a closure for said aperture, an over flow pipe leading from the lower part of said casing, an over flow leading from the upper end of said chamber, a sight opening in the last said over flow, a pipe leading from the upper end of said casing and communicating with the upper end of said chamber and a valve in said pipe, substantially 90 as described.

95 11. In a device of the class described, a casing, a spiral wall in said casing forming a passage way, a water seal for the lower end of said passage way, said casing being provided with a clean out opening below 100 the level of said water seal, a clean out chamber in communication with said casing through said clean out opening, there being an aperture in the upper portion of said chamber; a closure for said aperture, a liquor over flow pipe leading from the lower end of said casing, an overflow pipe leading from the upper end of said chamber, a trap shell in communication with the last said pipe and provided with a sight 105 opening, a drain pipe extending upwardly into said shell to the normal liquor level, a pipe extending from said casing and provided with branches in communication with said chamber and said shell respectively, 110 115 and a valve in said pipe, substantially as described.

12. In a device of the class described, a casing, a horizontal perforated partition in said casing dividing the same into an upper 120 separating chamber and a lower or tar chamber, a spiral wall in said separating chamber and resting on said horizontal partition, a water seal extending above the lower end 125 of said spiral wall, a clean out chamber, there being an aperture in the wall of said casing forming a communication between said clean out chamber and said tar chamber, said clean out chamber being provided with a clean out opening and a closure for 130

said opening, a liquor over flow for said casing, a liquor over flow for said clean out chamber, a pipe extending from said separating chamber to the upper portion of said 5 clean out chamber and a valve in said pipe, substantially as described.

13. In a device of the class described, a casing, a spiral wall in said casing forming a spiral passage way, inlet and outlet ports 10 in communication with the ends of said passage way respectively, a water seal for the lower end of said passage way and means governed directly by the pressure in said passage way for varying the level of said water seal, substantially as described.

14. In a device of the class described, a gas passage way, and means controlled directly by the pressure of gas in said passage way for varying the cross sectional area 20 thereof inversely proportionately to the pressure, substantially as described.

15. In a device of the class described, a spiral passage way, a water seal for the lower end of said passage way, an over flow 25 and means governed directly by the pressure of gas in said passage way for varying the height of said over flow, substantially as described.

16. In a device of the class described, a 30 casing, a spiral wall in said casing forming a spiral passage way, inlet and outlet ports in communication with the ends of said passage way respectively, a water seal for the lower end of said passage way and means 35 for varying the level of said water seal consisting of a fluid receptacle, a pressure bell slidably arranged within said receptacle, a pressure pipe in communication with said bell, an overflow outlet connected to the bottom of said casing, means between said bell 40 and said over-flow outlet for raising and lowering the latter upon variation of the pressure in said casing and a source of water supply for said casing, substantially as described.

17. In a device of the class described, a casing, a spiral wall in said casing forming a

spiral passage way, inlet and outlet ports in communication with the ends of said passage way respectively, a water seal for the 50 lower end of said passage way, an outlet connected to the bottom of said casing, an over-flow spout slidably arranged within said outlet, a fluid receptacle adjacent said casing, a pressure bell slidably mounted for 55 vertical movement within said receptacle, a pressure pipe within said receptacle and communicating between said bell and said casing, a shaft adjacent said fluid receptacle, means between said bell and said shaft for 60 rotating the latter upon raising and lowering said bell, additional means between said shaft and said over-flow spout for raising and lowering the latter and a source of water supply for said casing, substantially 65 as described.

18. In a device of the class described, a casing comprising an upper separating chamber and a lower tar chamber, a spiral wall in said separating chamber, a water seal extending above the lower end of said spiral wall, an outlet pipe connected to said tar chamber, an over-flow outlet slidably connected to said outlet pipe, a fluid receptacle above said overflow outlet and adjacent said casing, a pressure bell slidably arranged within said receptacle, a pressure pipe communicating between said bell and said casing, a shaft adjacent said receptacle, means between said shaft and said bell for 70 75 rotating the former upon raising and lowering of the latter, additional means between said shaft and said over-flow outlet for raising and lowering the latter upon the rotation of said shaft and a source of water supply for said casing, substantially as described.

In testimony whereof I have signed my name to this specification in the presence of two subscribing witnesses.

CLAUDE E. REESE.
